UNITED STATES PATENT OFFICE.

JAMES SCOTT ST. BARBE BAKER, OF LONDON, ENGLAND.

DESIGN FOR A BOTTLE.

Application filed December 26, 1924. Serial No. 11,807. Term of patent 14 years.

To all whom it may concern:

Be it known that I, JAMES SCOTT ST. BARBE BAKER, a subject of the King of Great Britain, residing at 51 and 52, Andrews Road, Hackney, London, England, have invented a new, original, and ornamental Design for a Bottle, of which the following is a specification, reference being had to the accompanying drawing, forming part thereof.

In the accompanying drawings:

I claim:—

The ornamental design for a bottle substantially as shown.

JAMES SCOTT ST. BARBE BAKER.
